CLAIM

The ornamental design for a breast pump as shown and described.

DESCRIPTION

FIG. 1 is a perspective view showing a first embodiment of a breast pump;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof.

FIG. 8 is a perspective view showing a second embodiment of a breast pump;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The portions of the breast pump shown in broken lines form no part of the claimed design.

1 Claim, 14 Drawing Sheets
